UNITED STATES PATENT OFFICE.

JOSEPH BOYER, OF DETROIT, MICHIGAN, ASSIGNOR TO BURROUGHS ADDING MACHINE COMPANY, A CORPORATION OF MICHIGAN.

CARRYING MECHANISM FOR ACCOUNTING MACHINES.

Application filed January 13, 1926. Serial No. 80,945.

The invention relates to a carrying mechanism for accounting machines.

Its general object is to provide an improved carrying mechanism for such machines.

A more particular object is to provide a carrying mechanism that is positive in operation; one that will not be moved to an undesired position by the jar or vibration of the machine; one that is made of a minimum number of parts; one that may be conveniently manufactured; and one that is more simple, visible, and accessible for assembly adjustment and repair.

15 Other objects and advantages of the invention will hereinafter appear.

An embodiment of the invention is illustrated in the drawing in which:

Fig. 1, is a side elevation of an accounting machine with the carrying mechanism mounted on it.

Fig. 2, is a cross-section of the carrying mechanism showing the parts in certain positions which will be later described.

25 Fig. 3, is a plan view of the front portion of the carrying mechanism together with its frame, and the totalizer associated with it.

Fig. 4, is a sectional plan view on the line 4—4 of Fig. 2.

30 Fig. 5, is a perspective view of one series of moving parts of the carrying mechanism.

Fig. 6, is a side elevation and section showing the series of moving parts of the carrying mechanism in different position than in Fig. 5.

Fig. 7, is a view similar to Fig. 6, showing the parts in position for resetting or latching the carrying mechanism.

40 Fig. 8, is a vertical section on line 8—8 of Fig. 2.

The carrying mechanism is illustrated in connection with a Burroughs Moon-Hopkins accounting machine, but is to be understood that it is not confined to association with this machine and that it may be used with other makes and types of machines. Only the general features of the Burroughs Moon-Hopkins Machine will be described, reference being made to Hopkins Patent No. 1,336,904 for details.

The accounting machine has a plurality

of depressible keys 10, arranged to operate levers 11 pivoted at 12. These levers press upwardly on vertical bars 13, which in turn set pins 14 in a traveling carriage 15. When one of the keys 10 is depressed, a pin 14 corresponding to that key is pushed upwardly. When the key is released, the carriage 15 automatically moves over one space 60 and another row of pins 14 is positioned so as to be engaged by one of the vertical bars 13 when another of the keys 10 is depressed. In this manner, one pin 14 in each of a number of banks of such pins is elevated corresponding to the keys that have been depressed to put a given figure into the machine.

After the proper number has been put into the machine, an operating handle (not shown) is moved forward. This elevates the carriage 15, and the pins 14 that have been pushed upwardly strike movable stops 16 and elevate a series of those stops corresponding to the pins 14 that have been pressed upwardly. The stops 16 project into the path of a series of actuator bars 20, each of which is provided with a lug 21 for engaging the stop 16 which may be in its path. Movement of the operating lever also releases the arms 22 which are normally biased forward by springs 23. These arms are connected to the actuator bars 20 and, as they move forward, they carry the actuator bars with them. The bars move forward until their projections 21 engage the respective stops 16 that may be in their path. They thus move forward different distances which are proportional to the values of the keys that have been depressed. The front ends of the actuator bars 20, carry type bars 24, which are struck by the hammers 25 of a printing mechanism which need not be described. The actuator bars are returned to their normal position by the return movement of the operating handle.

A front totalizer 30 and a rear totalizer 31 are operated by the actuator bars. These totalizers are carried by frames 32 and 33 respectively, pivoted at 34 and 35 so that either totalizer may be moved into and out of engagement with the actuator bars. When the actuator bars 20 are moved forward, neither of the totalizers is in mesh

with the actuator bars, but, prior to the rearward movement of the actuator bars, the desired totalizer is moved into engagement with the bars so that as the bars are returned to their normal rearward position, the movement of the arms will be accumulated in the totalizer. The two totalizers are substantially the same and the carrying mechanism for each is similar so that only one totalizer with its carrying mechanism will be described.

The totalizer 30 includes a series of toothed totalizer wheels which are, beginning with the right wheel when the machine is viewed from the front, the units wheel, the tens wheel, the hundreds wheel, etc. The number of wheels depends on the size of the machine. There may be two or more sets of totalizer wheels on the same shaft. By shifting the wheels lengthwise any set may be brought into line with the actuator bars to accumulate in different totalizers.

When any one of the totalizer wheels has been rotated through a complete revolution, its rotation must be registered on the wheel of next higher order. This is done by causing the wheel of next higher order to be moved forward one step or tooth and the present invention relates particularly to carrying mechanism for accomplishing this purpose.

The carrying mechanism includes a series of moving parts for each totalizer wheel, the parts actuated by one wheel serving to impart a one step movement to the wheel of next higher order. Each series of moving parts is similar and, in order not to complicate the description, only one series will be described. The whole series of parts is mounted on a shaft carried by two side frame members 36 and 37, pivoted at 38 and 39 as illustrated in Fig. 3.

Each totalizer wheel has one tooth 40 which is wider than the others and which forms a lateral projection that strikes the end of a pendant pawl 41 pivoted on a cross shaft 42 and having its movement in one direction limited by the stop 43. The pawl 41 carries a projection or ear 44 that contacts the tail of a second pawl or latch 45, pivoted at 46. The latch 45 has a hooked upper end 47 which normally engages over a shoulder 48 on the lever arm 49, as illustrated in Fig. 5. This lever arm has a downwardly projecting portion 50 to which is connected one end of a spring 51, the other end being connected to the latch 45 below its pivoted center so as to tend to turn the latch counter-clockwise. This spring also serves to normally bias the lever 49 in a clockwise direction. It thus acts to maintain the end of latch 45 hooked over the shoulder of lever 49, as illustrated in Fig. 5. The lever 49 is pivoted at 52 to the outer end of one of the arms 53 of a bell crank carry member or

arm 54. It is provided with a slot 55 of slightly greater width than the diameter of the shaft 56 carried by the frame.

The carry arm 54 is pivoted on the shaft 56 and its lower end is provided with teeth 57 which are adapted to mesh with the teeth of the totalizer wheel of next higher order than the wheel which sets the arm into operation. All of the carry arms 54 are held against operation by a U-shaped bail 57 pivoted on the shaft 56 and extending under all the carry arms. This bail serves as a means for restoring the carry arms to normal position after they have effected a carry.

The operation of the carrying mechanism is as follows:

Starting with the parts in their normal position as illustrated in Fig. 5, assume that the totalizer wheel 40 passes beyond its nine position. During this movement the tooth 40 or projection 40 passes the end of the pawl 41 and as it passes the pawl, it pushes the pawl outward and the projection 44 moves the latch 45 in a clockwise direction which moves the hooked end 47 beyond the shoulder 48 of arm 49. This releases the arm 49 and the spring 51 turns it in a clockwise direction about pivot 52. Its movement is limited by the contact of lower edge of the slot 55 with the shaft 56. This slot is made wide enough so that the movement of the arm 49 will be sufficient to raise the shoulder 48 above the hooked end 47 of the latch 45 as shown in Fig. 6. This prevents the latch 45 from again locking the arm 49 when the latch moves back toward normal position after the projection 41 has passed pawl 42.

After the lower edge of the slot 55 in arm 49 has contacted with the shaft 56 the pull of spring 51 tends to swing the arm about the axis of shaft 56 and this, in turn, tends to swing the carry arm 54 in a clockwise direction. Such movement is prevented, however, by the bail 57, which, at that time, is in contact with the carry arms as illustrated in Fig. 2. The above movements take place while the totalizer wheels are in mesh with the actuator bars and before the wheels have been moved upward into engagement with the carry arms. As the operating handle of the machine reaches the end of its forward stroke, the totalizer is raised out of engagement with the actuator bars and into engagement with the carry arms except the units wheel which engages the fixed stop 58. At the same time the bail 57 is lowered and this permits the springs 51 to swing the arms 49 together with their released carry arms 54 in a clockwise direction. This movement is limited by the contact of the ends of the carry arms with an adjustable stop shaft 60 which has a cut away portion and which may be adjusted by turning the shaft to vary the position of the cut away portion. The stop

shaft is positioned so that the movement of the carry arms is just enough to move the totalizer wheels with which they engage one unit.

- 5 The carry arms and associated parts are returned to normal position by the bail 57 which is swung in a counterclockwise direction to the position illustrated in Fig. 7. The bail returns all the carry arms to normal 10 position at the same time. This return movement is sufficient to permit the parts to move so as to carry the shoulders 48 of arms 49 slightly past the hooked ends 47 of the latches 45 as illustrated in Fig. 7. This insures that the clearance will be great enough 15 to permit the latches 45 to snap into position to latch the arms 49 against movement.

The mechanism for operating the bail 57 is illustrated in Fig. 2. It includes a disc 70 moved by the operating handle of the machine and having a cam portion 71, a concentric portion 72 and a depressed portion 73. The edge of the disc travels under a pass-by pawl 74 pivoted at 75 to the vertically movable member 76. This pawl is provided on one end with a tail piece 77 engaging the stop 73 and on its other end with a roller 79 for engaging the edge of the disc. The vertically movable member 76 is connected to 20 an arm 80 which is integral with the bail 57 so that movements of member 76 are transmitted directly to the bail. A similar set of operating devices is provided for the rear totalizer bail, but as the parts are similar, 25 the second set will not be described. It is partly illustrated in Fig. 2.

As the operating lever of the machine is pulled forward in Fig. 2, the disc 70 has no effect in operating the bail because the pawl 30 74 rides loosely over the disc. During this movement of the handle the totalizer wheels are in raised position, that is, out of contact with the actuator bars and in mesh with the carry arms. At the beginning of the return 35 movement of the handle, the totalizer wheels are lowered out of mesh with the carry arms and into mesh with the actuator bars. At about the same time the cam portion 71 of the arm 70 moves the bail operating bar 76 40 upwardly and the bail is moved in a counterclockwise direction to restore the carry arms and associated mechanism to a normal position. During this restoring operation the cam face 71 raises the arm 76 and moves the bail 57 slightly beyond normal position to insure that the shoulders 48 are carried below the hooked ends 47 of latches 45 after 45 which the roller stud 79 drops off the high point of the cam face 71 onto the concentric portion 72 which allows the parts to move to normal position. During the time that the roller stud 79 is traveling on the concentric surface 72, the totalizer wheels are being rotated by the actuator bars and if a carry 50 takes place, the appropriate latches are

tripped to occupy the position shown in the forward totalizer of Fig. 2. After the actuator bars have been returned to their normal position, the further movement of the operating lever raises the totalizer wheels into 55 contact with the carry arms and shortly thereafter the roller stud 79 drops into the depressed portion 73 of the disc 70, thereby allowing the bail 57 to drop which, in turn, permits the carry arms to be actuated and 60 carry the necessary amounts forward on the totalizer wheels.

Among the advantages of the improved carrying mechanism is the fact that one spring, namely the spring 51 serves to operate three parts, the latch 45, the arm 49, and the carry arm 54. This and the relation of the different elements reduces the number of parts required. Another advantage is that the operation is positive and the parts 65 cannot be displaced by jar or vibration of the machine. A still further advantage is that the movement of the parts is readily visible and they are easily accessible thereby making it easy to assemble, service and adjust the mechanism. An additional advantage is that the manufacturing processes are simplified, particularly in that the position 70 of the carry arm does not depend upon the accuracy of numerous other parts. The relation of the teeth of the carry arm to the surface of the arm which contacts the bail 57 75 may be easily maintained in the manufacture of the carry arms.

It is to be understood that the construction 80 shown is for purposes of illustration only and that variations may be made in it without departing from the spirit and scope of the invention as defined by the appended claims.

I claim:

1. The combination in a carrying mechanism of a carry arm, an actuating lever for said arm, a latch for said lever, and a single means for actuating both the lever and the latch.
2. The combination in a carrying mechanism of a carry arm, an actuating lever for said arm, a latch for said lever, and a spring for actuating both the lever and the latch.
3. The combination in a carrying mechanism of a carry arm, an actuating lever movable relative to the arm, a latch for said lever, and a single means for biasing the latch to latched position, for moving the lever relative to the arm, and for moving the arm.
4. The combination in a carrying mechanism of a carry arm, an actuating lever having a limited movement relative to said arm, a latch for said lever, and a single spring for biasing the latch to latched position, for moving the lever relative to the arm, and for moving the arm.
5. The combination in an accounting ma-

- chine of totalizer wheels having tripping projections, pendant pawls operated by said projections, pivoted latches operated by said pawls, said latches having hooked ends, pivoted levers having shoulders for engagement under the hooked ends of the latches, and toothed carry arms to which the levers are pivoted, said carry arms having operative relation to said totalizer wheels.
10. 6. The combination in an accounting machine of totalizer wheels having tripping projections, pendant pawls operated by said projections, pivoted latches operated by said pawls, said latches having hooked ends, pivoted levers having shoulders for engagement under the hooked ends of the latches, toothed carry arms to which said levers are pivoted, and springs each of which operates a latch, a lever and a carry arm, said carry arms having operative relation to said totalizer wheels.
7. The combination in an accounting machine of totalizer wheels having tripping projections, pendant pawls operated by said projections, latches operated by said pawls, said latches having hooked ends, bell crank carry members pivoted near the juncture of their arms, one of the arms of the bell crank levers having teeth which are in operative relation to the totalizer wheels, and levers pivoted to the other arms of the carry members, said levers having shoulders for engagement under the hooked ends of the latches.
35. 8. The combination in an accounting machine of totalizer wheels having tripping projections, pendant pawls operated by said projections, latches operated by said pawls, said latches having hooked ends, a shaft, bell crank carry members pivoted to said shaft near the juncture of their arms, one arm of the bell crank levers having teeth which are in operative relation to the totalizer wheels, and levers pivoted to the other arms of the carry members, said levers having slots for receiving said shaft to permit slight movement of the levers relative to the shaft, said levers also having shoulders for engagement under the hooked ends of the latches.
50. 9. The combination in an accounting machine of totalizer wheels having tripping projections, pendant pawls operated by said projections, latches operated by said pawls, said latches having hooked ends, a shaft, bell crank carry members pivoted to said shaft near the juncture of their arms, one of the arms of the bell crank levers having teeth which are in operative relation to the totalizer wheels, and levers pivoted to the other arms of the carry members, said levers having slots for receiving the shaft which slots are of slightly greater width than the diameter of the shaft to permit a limited movement of the lever relative to the shaft, said levers also having shoulders for engagement under the hooked ends of the latches, and springs connected to arms on the levers and to the latches.
10. The combination in an accounting machine of totalizer wheels having tripping projections, toothed carry members in operative relation to the totalizer wheels, said carry members being biased to move in one direction, means for normally holding the carry members against movement in said direction, levers pivoted to the carry members and normally biased to move on their pivots, means for limiting the movement of the levers on their pivots on the carry members, latches for normally preventing movement of the levers, and means operated by the tripping projections on the totalizer wheels for momentarily moving the latches to release the levers to permit them to move a limited distance.
11. The combination in an accounting machine of totalizer wheels having tripping projections, toothed carry members in operative relation to the totalizer wheels, clearing means for holding the carry members against movement, levers pivoted to the carry members, means for limiting the pivotal movement of the levers relative to the carry members, latches for normally preventing movement of the levers and carry arms, springs, each of which acts to normally move a latch, a lever and a carry arm of a set, and means operated by the tripping projections on a totalizer wheel for momentarily moving the latches to release the levers to permit them to move a limited distance relative to the carry arms to unlatch the carry arms to permit them to move when released by the clearing means.
12. The combination in a carrying mechanism of a carry arm normally urged in a direction to effect a carry, a member connected to said arm and normally latched in position to prevent movement of the arm, means for unlatching said member, and means for yieldingly holding said member in its unlatched position.
13. The combination in a carrying mechanism of a carry arm, a member connected to said arm, a latch for preventing movement of said member, means for urging said member toward unlatched position, and means for moving the latch to unlatched position, said urging means being connected to said latch to hold it in latched position and acting to hold said member and latch in unlatched position after they have been unlatched.
14. The combination in a carrying mechanism of a movable carry arm, a lever pivoted to said arm and having a limited movement relative thereto, means for urging said lever in a direction to move it relative to the

carry arm and to move the carry arm in a carrying direction, means for holding the carry arm against movement, latching mechanism for holding the lever against movement, tripping means actuated by a tripping projection on a counter wheel for releasing the latching mechanism to permit the lever to move to effect an initial carry, and means for releasing the carry arm holding means to permit the carry arm to move to effect a full carry. ¹⁰

In testimony whereof, I have subscribed my name.

JOSEPH BOYER.
